Des. 183,474
Patented Sept. 2, 1958

183,474

COMBINED SAMPLE CARRYING AND DISPLAY CASE

Ralph L. Wintersteen, Skaneateles, N. Y.

Application June 18, 1957, Serial No. 46,635

Term of patent 14 years

(Cl. D80—11)

Fig. 1

Figure 1 is a front perspective view of a combined sample carrying and display case in an open position, embodying my new design, the rear being substantially plain; and

I claim:

The ornamental design for a combined sample carrying and display case, as shown and described.
